CORNER JOINERY IN SASH

Ward P. Kessler, Bristol, Ind., assignor to Victor
M. Langseth, Chicago, Ill., as trustee

Application October 2, 1946, Serial No. 700,693

7 Claims. (CL. 189—76)

1

This invention relates to improvements in the corner joinery of sash members, particularly building window sash, and methods related thereto.

The sash frames are preferably made of formed metal or metal alloy sections by extrusions but it is readily apparent that any formed material, plastics for example, may be used.

An object of my invention is to provide an efficient and cost reducing method of joining sash members at their ends by telescoping a rail and cross-member, forming a corner of the sash, and imparting rigidity by impinging or embossing a portion of the structure or by mechanical means and covering the upper orifice in the perpendicular rail.

Another object is to provide a satisfactory corner structure in window sash by interlocking the end of a rail and the end of a cross-member, taking advantage of the rigidity resulting from the form of the members, and the method of telescoping and positioning said members.

Another object is to provide mechanical assembly thereby avoiding welding or brazing the members.

Another object is to permit the surface finishing of the members before assembly.

Further objects and advantages of the invention will be apparent from the following specification and the accompanying drawings, wherein a preferred embodiment of the invention has been shown and described.

In the drawings:

Figure 1 is a perspective view of a sash rail and cross-member joined, disclosing the ends of said members telescoped forming a corner of the sash.

Figure 2 is an exploded view of the structure shown in Figure 1.

Figure 3 is a perspective view of an assembled sash corner and particularly illustrating the method of impinging and embossing the rail to give rigidity to the structure.

Figure 4 is a perspective view of the means used to cover the upper opening in the perpendicular rail.

Figure 5 is a vertical view, partly in section, showing the said cover in position.

Figure 6 is a perspective view of a sash rail and cross-member joined disclosing the adaptation of a structural form of the members varying from that shown in Figure 1.

Figure 7 is an exploded view of the structure shown in Figure 6.

Figure 8 is a perspective view of the assembled

2

sash corner using the structural form shown in Figures 6, 7 and 10.

Figure 9 is a perspective view of the cover means used in the corner assembly Figure 8.

5 Figure 10 is a vertical view, partly in section, showing the use of mechanical means, in addition to impingement, to give rigidity to the structure.

Figure 11 is a perspective view disclosing the adaptation of another structural form of the members.

Figure 12 is an exploded view of the structure shown in Figure 11.

15 Figure 13 is a perspective view disclosing the adaptation of a further structural form of the members.

Figure 14 is an exploded view of the structure shown in Figure 13.

20 The complete window frame and sash have not been shown in the drawings. However, it should be obvious that any sash possesses a plurality of corners, usually four in number, and that my invention would apply to any of such corners and that the detailed description herein as to one corner, refers to all with the apparent variance required between a right hand and left hand application. The sash itself, preferably of the double hung type, as indicated in the drawings, is designed to operate within a frame with a fixed upper sash, but I do not confine myself to this particular adaptation of my invention.

25 Similar numerals refer to similar parts throughout the several views.

30 Referring to Figures 1 to 5 of the drawings, the sash corner structure has a formed cross-member 1, substantially rectangular in cross-section, preferably with a hollow center, one side wall of which has an inturned L-shaped elongation 2 and the adjoining side wall nearest said

35 elongation, has an obtrusion 3, the outside surfaces of said obtrusion 3 and the inturned lip of the elongation 2 being substantially on the same plane, forming a recess 4 for putty retention and providing a support for the glass pane.

40 The sash corner also has a formed side rail 5 preferably with three side walls to save material. Similarly, the side walls of the cross-member 1 need not be closed as indicated in Figure 12.

45 This rail 5 has one side wall with an outwardly and upwardly turned leg 6, forming the channel 7, the width of which is approximately equal to the thickness of the side wall 8 of the cross-member 1, and the obtrusion 9 on the outside of the other end, of a height substantially less than the thickness of said side wall 8. Another side

wall of the rail 5, opposite that described above, has an inturned L-shaped elongation 10. The side wall connecting the above two side walls has an obtrusion 11, which, with the elongation 10, forms a recess 12 for putty retention and also provides a support for the pane of glass. The above form of the cross-member 1 and rail 5 gives strength to the members and facilitates my method of corner joinery. The over all dimensions and weight of material used in the members are determined by the size of the sash and the particular application desired.

In preparing the members for joining, a portion of an end of the cross-member 1 is removed at substantially right angles to its axis, leaving the side elongation 8, in which a channel 13 is made to accommodate the obtrusion 9, and the slot 14; and the grooves 15 and 16 cut, at substantially right angles to the axis of said member, of sufficient width and depth to accommodate the obtrusion 11 and the inturned leg of the elongation 10, respectively. A slot 17 is cut in the end of the inner wall of the rail 5 of sufficient width and depth to accommodate the stud 18 of the cover 34. This cover member 34 is of sufficient size to cover the opening in the top of the rail 5, caused by its form which is channel shaped in cross-section, adding a finished appearance and preventing the admission of foreign objects. It is held in position by the substantially T-formed stud 18 on its bottom side, which also assists in the mechanical joinery. In practice, the substantially rectangular cover 34 and the stud 18 are extruded as an integral piece but they can be fastened together, as separate pieces, by other means, such as welding the upturned lip on the cross bar of said stud 18 to the base of the cover 34. The corner joinery is accomplished by placing the prepared end of the cross-member 1 in contact with the end of the side rail 5, insert the stud 18 in position with the recess 17 and then sliding and telescoping the two members into position, the elongation 8, channel 13 and grooves 15 and 16 in the member 1 intimately embracing or being embraced by the channel 7, obtrusions 9 and 11 and inturned lip of the leg 10, and the cover held in position by the contact of the stud 18 with the upper wall of the member 1 and the inner wall of the member 5 as shown in the cross-sectional view of Figure 5. In order to give greater rigidity to the structure and supplement the immobility of the members resulting from their impingement, the obtrusion 11 is distorted, embossed, or other equivalents thereof, on both sides of its point of contact with the inturned lip of the elongation 2 as shown at 19 and 20, respectively, and the upturned lip of the leg 6 is distorted, embossed, or other equivalent thereof, at its point of contact with the recess 14 as shown at 21.

A simplified structural form of the members is shown in Figures 6 to 10, inclusive. The cross-member 22 in this form is similar to the cross member 1 shown in Figures 1, 2, 3 and 5, inclusive, except that the obtrusion 3 has been eliminated. The side rail 23 is similar to the side rail 5 shown in Figures 1 to 5, inclusive, except that the obtrusions 9 and 11 have been eliminated. Also, in preparing the ends of the member for joining, the channel 13, slot 14 and groove 15 shown in Figure 2, have been eliminated in the cross-member 22. Movement of the members along the axis of the side rail is prevented by mechanical means, preferably the screw 24 in-

serted in the hole 25 in the side rail and the hole 26 in the cover after the assembly of the members.

Likewise, in the structural form shown in Figures 11 and 12, the obtrusion 3 shown in Figures 1, 2, 3 and 5, has been eliminated, as well as the groove 15 in the cross-member 27. In order to save material, in some instances it may be desirable to avoid the use of a closed structural form in the cross-member by leaving an opening between two of the sides as shown at 29. Similarly, it is readily apparent that that portion of the lower side of the cross-member 1 shown in Figure 3 between the obtrusion 3 and the side with the elongated leg 2, can be eliminated without substantially affecting the structural strength of the member and thereby secure a saving in material. Also, the obtrusion 11, shown in Figures 1, 2, 3 and 5, has been eliminated from the side rail 28, Figures 11 and 12. Movement of the members along the axis of the side rail is prevented by distortion as shown at 21 in Figure 5.

In Figures 13 and 14, the structural form of the members is similar to that shown in Figures 11 and 12, with the addition of the channel 30 in the exterior surface of the elongated side of the cross-member 31 to accommodate and embrace the inturned leg 33 of the side rail 32, thereby increasing the surface area impinging at the corner joint and also creating a greater locking action.

It is readily apparent that a modified method of embossing as shown in Figure 5, or mechanical means, shown in Figure 10, to prevent movement of the members along the axis of the side rail, can be adapted to any of the illustrations. The terms "corner joinery" and "corner joint" are used herein synonymously.

While I have shown and described herein, for illustrative purposes, a preferred and alternative embodiment of the invention and method of practicing it, it should be understood that considerable variation in the details of construction may be employed and the method varied, without departing from the spirit and scope of the invention, as set forth in the following claims.

I claim as my invention:

1. In combination with a formed sash cross-member and a formed side-rail, channel shaped in cross-section, said cross-member interlocked at its end with the end of said side-rail, forming a sash corner, a formed cover comprising a substantially rectangular base with a substantially T-shaped stud having an upturned lip upon the cross-bar of said T attached to the bottom of said base, the end of an upper side wall of said cross-member being received between the bottom of said base and the top of said stud, the downwardly extending leg of said stud abutting against an adjacent side wall of the said side-rail, closing said channel in said side-rail at its upper end, and means, including a screw inserted through adjacent holes in said stud and side-rail, and retaining said cross-member and side-rail in position relative to each other.

2. A sash corner joint comprising, in combination, a corner cap member, an extruded sash cross member of generally rectangular tubular cross section, one vertical wall of the tubular member being extended laterally outside the tube area and having integral therewith an inwardly turned longitudinally extending flange at right angle thereto constituting an abutment for a glass panel, an extruded sash side rail member of generally channel shape in cross section, the channel of which opens outwardly in the plane 75 of the sash, one channel side wall being extended

beyond the channel bottom wall and having an inwardly turned longitudinally extending flange at right angle thereto constituting an abutment for a glass panel, a second wall portion of the tubular cross member being extended longitudinally beyond the other three wall portions thereof and having a lock recess in its terminal edge, one channel wall of the side rail member having a flange turned outwardly thence inturned inwardly to snugly embrace said extended wall portion of the cross member, a detent struck out from said inturned flange bent into said lock recess, the cross member having a recess near an end thereof extending transversely of the aforesaid cross member inturned flange and the said extended wall with which it is integral, the first said flange of said side rail member snugly fitted into said transverse recess, the cap member having a plate portion covering the end of the channel member, a leg depending from said plate portion adjacent said channel member, and means locking said leg immovably relatively to the cross and side rail members.

3. A sash corner joint comprising, in combination, a corner cap member, an extruded sash cross member of generally rectangular tubular cross section, one vertical wall of the tubular member being extended laterally outside the tube area and having integral therewith an inwardly turned longitudinally extending flange at right angle thereto constituting an abutment for a glass panel, an extruded sash side rail member of generally channel shape in cross section, the channel of which opens outwardly in the plane of the sash, one channel side wall being extended beyond the channel bottom wall and having an inwardly turned longitudinally extending flange at right angle thereto constituting an abutment for a glass panel, a second wall portion of the tubular cross member being extended longitudinally beyond the other three wall portions thereof and having a lock recess in its terminal edge, one channel wall of the side rail member having a flange turned outwardly thence inturned inwardly to snugly embrace said extended wall portion of the cross member, a detent struck out from said inturned flange bent into said lock recess, the cross member having a recess near an end thereof extending transversely of the aforesaid cross member inturned flange and the said extended wall with which it is integral, the first said flange of said side rail member snugly fitted into said transverse recess, the cap member having a plate portion covering the end of the channel member, and means retaining said cap member immovably relatively to the side rail and cross members.

4. A sash corner joint comprising, in combination, an extruded sash cross member of generally tubular cross section, one vertical wall of the tubular member being extended laterally outside of the tubular area and having integral therewith an inwardly turned longitudinally extending flange at right angle thereto constituting an abutment for a glass panel, an extruded sash side rail member of generally channel shape in cross section positioned with the channel opening outwardly in the plane of the sash, one channel side wall being extended beyond the channel bottom wall and having an inwardly turned longitudinally extending flange at right angle thereto constituting an abutment for a glass panel, and a second vertical wall portion of the tubular member overlapping and lying in snug contact with the second side channel wall of the side rail member and means restraining these two walls against

relative movement, the cross member having a slot near the corner end thereof extending transversely through its own inturned flange and the wall with which said flange is integral, said slot snugly receiving the inwardly turned longitudinal flange of the sash side rail.

5. A sash corner joint comprising, in combination, an extruded sash cross member of generally tubular cross section, one vertical wall of the tubular member being extended laterally outside of the tubular area and having integral therewith an inwardly turned longitudinally extending flange at right angle thereto constituting an abutment for a glass panel, an extruded sash side rail member of generally channel shape in cross section positioned with the channel opening outwardly in the plane of the sash, one channel side wall being extended beyond the channel bottom wall and having an inwardly turned longitudinally extending flange at right angle thereto constituting an abutment for a glass panel, and a second vertical wall portion of the tubular member overlapping and lying in snug contact with the second side channel wall of the side rail member and means locking said leg immovably relatively to the cross and side rail members.

10 30

6. A sash corner joint comprising a cross-member, substantially rectangular in cross-section, with one side wall thereof having an elongated, inturned leg and a transverse groove across said side wall and leg accommodating an inturned leg of a side-rail, the side wall of said cross-member opposite the first above mentioned side-wall having an elongation with a slot in its end and a transverse channel in its exterior face accommodating an inturned end portion of a leg of a side-rail; a side-rail, channel shaped in cross-section, having two opposite substantially parallel side walls, one of said side walls having an outwardly extending leg with an inturned end portion and the other side wall, an inturned leg, the end of said cross-member slidably engaging the end of said side-rail forming the sash corner, the side wall elongation of said cross-member abutting said outwardly extending leg of said side-rail, the inturned end portion of said leg being disposed in said transverse channel in said elongation of the cross-member side-wall, and the other inturned leg of said side-rail disposed in said transverse groove on said cross-member; and means retaining said cross-member and side-rail in position relative to each other.

7. A sash corner joint comprising a cross-member, substantially rectangular in cross-section, with one side wall thereof having an elongated, inturned leg and a transverse groove across said side wall and leg accommodating an inturned leg of a side-rail, the side wall of said cross-member opposite the first above mentioned side wall having an elongation with a slot in its end and a transverse channel on its interior face adjacent to the ends of two webs adjoining the aforementioned side walls, one of said webs having a longitudinal opening therein; a side-rail, channel-shaped in cross-section, having two substantially parallel side-walls and an adjoining inner wall, one of said side-walls having an outwardly turned leg and obstruction, and the other

side-wall, an inturned leg, and the end of the interconnecting inner wall having a recess accommodating the stud of a cover means, the end of said cross-member slidably engaging the end of said side-rail forming the sash corner, the side wall elongation of said cross-member abutting the outwardly turned leg of said side-rail with said obstruction disposed in said transverse channel in the interior face of said elongation, and the inturned leg of said side-rail disposed in said transverse groove in said cross-member; and means retaining said cross-member and side-rail in position relative to each other.
